UNITED STATES PATENT OFFICE.

MYRON L. SEVERSON, OF PASSAIC, NEW JERSEY.

FURNACE.

Application filed August 24, 1925. Serial No. 52,026.

This invention relates to improvements in furnaces, the general object of the invention being to provide a combined hot air and hot water furnace so that portions of 5 a building can be heated by hot air and other portions by hot water.

Another object of the invention is to provide the furnace with self-feeding means, such means being so arranged that a supply 10 of coal can be placed in the same from the outside of the furnace.

A further object of the invention is to so construct the furnace that the radiating surface of the same is greatly increased.

15 This invention also consists in certain other features of construction and in the combination and arrangement of the several parts, to be hereinafter fully described, illustrated in the accompanying drawings and 20 specifically pointed out in the appended claim.

In describing my invention in detail, reference will be had to the accompanying drawings, wherein like characters denote 25 like or corresponding parts throughout the several views, and in which:—

Figure 1 is a vertical sectional view through the invention.

Figure 2 is a section on line 2—2 of 30 Figure 1.

Figure 3 is a section on line 3—3 of Figure 1.

Figure 4 is a section on line 4—4 of Figure 1.

35 In these views, 1 indicates the ash pit part of the furnace and 2 the fire box part between which is the grate 3. The walls of the fire box part are formed with an annular water chamber 4, the lower part 40 of which is connected with a source of supply by the pipe 5 and the outlet pipe of which is shown at 6, the pipe 5 also acting as a return pipe when the pipes are connected to radiators or the like. The casing 45 7 is arranged above the part 2 and forms a combustion chamber, the lower part of which is in communication with the top part of the fire box. The walls of this casing 7 are corrugated so as to increase the 50 radiating surface of the combustion chamber and a ring-shaped water chamber 8 is placed on the top of the casing 7, the opening 9 of which permits the products of combustion to pass from said casing 7 into a cap 55 10 which is connected to a chimney by the ordinary smoke pipe through means of the

opening 11. A hook-shaped partition 12 is arranged in the cap so as to cause the products of combustion to pass in a circular path through the cap before escaping through the opening 11. A substantially S-shaped tube 13 passes through the middle part of the furnace and has its lower end arranged to discharge fuel into the fire box 2 with its upper end outside the furnace and covered by a door 14. This tube forms a self-feeder for the furnace, the fuel being placed in the same by opening the door 14. As the lower portion of the tube is arranged in the combustion chamber 7, this fuel will be heated before being discharged into the fire box. An exterior casing 15 and an interior casing 16 have their upper ends connected with the register 17 in the floor of the building and these two casings 75 form a cold air duct 18 for admitting cold air from the room above to the lower part of the exterior casing from where it passes into the space formed by the exterior casing and flows up the same through the central 80 part of the register into the room. The heater 8 can be connected to the hot water boiler or the like by the pipes 8' and a sight opening 19 is provided in the furnace so that the interior of the same can be seen. The 85 casing 16 and the fire box 2 are each provided with a cover 20 of asbestos or the like.

From the foregoing, it will be seen that the furnace is a combined hot air and hot water furnace with means for heating water 90 in a boiler. The self-feeding means can be easily filled from the exterior of the furnace and the burning of the fuel can be observed through the opening 19. The furnace is shown in the drawings as a pipeless one, but it will, of course, be understood that it can be provided with pipes for leading the hot air to the different rooms. The peculiar shape of the casing 7 increases the radiating surface of the furnace and the cap 10 and its partition 12 will cause the products of combustion to pass over the entire area of the top of the heater 8 before escaping to the chimney.

In starting the fire, the kindling is thrown into the feeder 13 and then it is ignited by throwing burning papers in the ash pit. Then the coal or other fuel is dumped into the feeder 13 to continue the fire.

A water tank 21 is in communication with 110 the air space of the furnace for moistening the air.

It is thought from the foregoing description that the advantages and novel features of my invention will be readily apparent.

I desire it to be understood that I may make changes in the construction and in the combination and arrangement of the several parts, provided that such changes fall within the scope of the appended claim.

What I claim is:—

- 10 A device of the character described including a fire box, an annular water chamber surrounding the fire box, an inner and an outer casing supported above the fire box, a water tank at one side of the fire box and

having communication with both the inner and outer casings, a third casing arranged within the inner casing having corrugated walls, a ring-like water casing at the top of said corrugated casing, a removable cap mounted upon said ring-like water casing, 20 the said cap carrying a hook-shaped partition to impede the progress of the products of combustion, and an S-shaped fuel feeding tube passing through the said casings with its inner end opening directly into the fire 25 box.

In testimony whereof I affix my signature.

MYRON L. SEVERSON.
